WELDER'S HELMET

Harold Roy Madson, Glen Ellyn, Ill., assignor to
Welding Apparatus Company, Chicago, Ill., a
corporation of Illinois

Application September 13, 1941, Serial No. 410,751

8 Claims. (Cl. 2-8)

The present invention relates to a welder's helmet having a swingable shield pivotally connected to and supported by a head harness fitting the head of the operator, and carrying a light-filtering lens, and also having means for opening and closing such lens by a movement of the operator's chin.

Among the objects of the invention is to provide a novel chin operated lens actuator which is normally located beneath the chin with a small clearance for allowing a given small amount of free and natural movement of the chin without effecting any movement of the novel actuator, yet being sufficiently proximate to the chin to be moved by the chin upon greater movements of the chin, whereby any desired opening of the lens will be accordingly effected to afford the operator with a free and uninterrupted view of the work between welding operations, at which time both of the hands of the operator are free for handling the work as desired. Such actuator also comprises novel means for adjustably supporting the actuator with reference to the chin for the operative relations referred to above.

Another object of the invention is to provide novel means which abuts against the chin for holding the shield and the lens means carried by the shield in such position in front of the operator's face that the lines of collimation of the operator's eyes will normally extend through the upper portion of the lens or through the upper portion of the lens aperture when the lens has been moved down into an open position. This novel chin abutting means also includes means for adjusting the abutting means with reference to the lens means to effect the above referred to relations.

A further object of the invention is the provision of a novel means for effecting a direct movement of the lens when the chin operated means is moved by the chin. This novel means comprises a bow shaped lever which is pivotally connected to the sides of the shield and rearwardly of the operator's chin, and with the mid portion of the bow lever extending transversely and forwardly of the operator's chin. The chin operated lens actuator referred to above may also be connected to such mid portion of the bow lever. From this mid portion of the bow lever forwardly extends a lens actuating element thus forming a leg of the bow lever. It is linked directly to the lens means. The point of application of the chin with the chin engaging actuator is intermediate of the pivots or fulcra of the lever and the point of linkage with the lens

means, whereby a given small movement of the chin operated lens actuator will be a fraction of the movement of the lens, thus requiring but a small movement of the chin for a larger movement of the lens effected directly by a simple lever movement and accordingly avoiding the complex and complicated lever systems heretofore found necessary, besides also eliminating the heretofore required large and extreme movements of the chin. By the present novel lens actuating means the operator is able to have better control of the extent of aperture opening above the lens, does not need to move his chin to as great an extent as heretofore, and avoids the tendency to fatigue of the jaw muscles.

The invention also comprehends novel connecting means between the lens means and the actuating device for the lens, and also novel means for compensating for manufacturing variances.

When making devices of the character disclosed on a production basis it is practically impossible to obtain uniformity of structure and relationship of the various elements of the construction. In the illustrative embodiment of the present invention the bow lever is connected to the sides of the shield by slot and pin means whereby the bow lever may be adjustably mounted to bring the lens actuating element secured to the mid portion of the bow lever into central position relative to the lens means. At such position the just referred to actuating element is connected by way of a link to the lens means. Such link is pivotally connected to the lens means and has an aperture of greater size than the end portion of the actuating element extending through such aperture to allow a certain amount of play in compensation for the manufacturing variances referred to above.

Another feature of the invention is the provision of a novel lens means, and particularly the holder or carrier therefor. The holder is open at the top so that the line of view will be past the upper edge of the lens itself when in partly opened position, hence avoiding the heretofore frame bar at the top of the lens which bar confused the operator and oftentimes gave rise to leakage of light by way of a crack below such bar and between it and the upper edge of the lens. By omitting such bar the required movement of the chin to lower the lens and its frame is reduced at least to the extent of the width of such bar if it were used. The operator, by the present invention, is able to obtain all the necessary view above the upper edge of the lens he desires by a slight movement of the chin and,

hence, a similar movement of the lens. It is not necessary to make the lens open so much as in the case when a bar is present because the view is obtained immediately over the upper edge of the lens without any confusion that would arise if a bar were there to cut off the view.

The lens also is designed to overlap along all its edges the surrounding frame sides to prevent leakage of light as might otherwise occur between an edge of the lens and the frame part at such edge. Also, the channels in which the lens and its carrier slide have means to so space the lens whereby as the lens is moved past the lower cross bar of the frame the lens surface will not contact with such bar and be marred or otherwise injured, as by scratching or the like.

Another novel feature is the provision of means whereby the actuator, when the lens is in closed position, is normally inclined a few degrees upwardly above the horizontal plane of the axis of the actuator lever, and is capable of being swung downwardly past such horizontal plane and a few degrees below it. In that way the component forward and rearward movement is reduced to a minimum.

A further novel feature is the provision of means for holding the lens open, as at full opening, whenever it is desired to have a direct and clear view of the work for a longer period of time than usual, and also to relieve the muscles from the effort of holding the lens open for such longer time. Such means includes a catch at a suitable locus below the actuator where the end of the actuating lever or element may engage such catch. All the operator needs to do is to lower his chin further than usual to the extent wherein the lens is substantially fully open, at which position the actuator lever engages the catch and is thus held by such catch. That frees the operator's chin. To unlatch the actuator lever, the operator merely presses a finger against the catch to disengage it from the end of the actuator lever whereupon the latter and the lens are moved upwardly by a suitable spring connected to the lever and the guard.

Other objects, capabilities, advantages, features and the like are comprehended by the invention as will later appear and as are inherently possessed by the invention.

Referring to the drawings:

Fig. 1 is a part side elevational and part sectional view of the invention shown applied to the head of an operator;

Fig. 2 is a fragmentary sectional view taken in a horizontal plane represented by line 2-2 in Fig. 5 of the drawings;

Fig. 3 is a fragmentary sectional view taken in a plane represented by line 3-3 in Fig. 1 of the drawings;

Fig. 4 is a horizontal sectional view taken in planes represented by lines 4-4 in Fig. 1 of the drawings;

Fig. 5 is a fragmentary rear elevational view with parts omitted and parts broken away, and taken in a plane represented by line 5-5 in Fig. 1 of the drawings; and,

Fig. 6 is a fragmentary perspective view of the lens guide feature.

Referring more in detail to the drawings, the embodiment selected to illustrate the invention is shown as comprising a shield normally located about the front portion of the operator's head to protect it during the welding operation.

The shield comprises a front wall 1 which covers the operator's face, side walls 2 and 3 which extend along the sides of the head, a top portion 4 for covering the forehead, and an underlying portion 5 extending about the chin portion of the head.

The shield is pivotally connected to and supported by a head harness, the latter comprising a head band 6 having its ends adjustable at the rear of the head and held in adjusted condition by a clamping means 7. Over the top of the head is a crown strip 8 having its lower ends suitably secured or fixed, as by rivets or the like, to the side portions of the head band 6, and having its upper ends adjustable and connected by suitable clamping means 9. The lengths of the head band 6 and the crown strip 8 may be adjusted manually to fit the head of the operator, after which the clamping means 7 and 9 are tightened to hold the head band and crown strip in adjusted condition.

The sides 2 and 3 of the guard are laterally spaced from the sides of the head band, and are connected thereto by friction pivot means, such as is shown in detail in Fig. 3.

Each pivot means comprises a stem 10 having a head 11 for bearing against the inner side of the head harness at the juncture of the head band 6 and the crown strip 8. The other end of the stem extends through a slot 12 provided in the side wall 3, or 2 as the case may be. The slotted portion of the side wall 3 or 2 is clamped between discs 13 and 14, the disc 13 being pressed by the flange of a nut 15 screwed on the threaded portion of the stem 10, and the disc 14 being pressed by way of a washer 16 in turn pressed by a nut 17 threaded to the end portion of the stem 10. Against the juncture of the head band 6 and the crown strip 8 is a washer 18 pressed by a spring 19 interposed between such washer 18 and the flange of the nut 15.

By adjusting the nut 15 on the stem 10 the spring 19 is compressed as desired to impose the desired friction between the head harness 45 and the washer 18. By adjusting the nut 17 the clamping of the side wall 3 between the discs 13 and 14 is effected as desired. The contacting surfaces between the crown strip 8 and the washer 18 on one side thereof and the head 11 50 on the other side thereof act as a friction means to retain the angular relation of the shield and the head harness. For example, whenever it is desired to move the shield from in front of the face of the operator, it may be swung upwardly 55 to the dotted line position shown in Fig. 1. The friction in the above described pivot means will be sufficient to hold the shield in such elevated position, and to prevent it from falling or idling down, yet will permit a forced downward swing 60 of the shield by the operator's hand when it is desired to bring the shield again opposite the operator's face.

The front wall 1 has an aperture 20 and a window structure with a movable light-filter lens. 65 The structure comprises outer and inner window frames 21 and 22 in registry with the aperture 20, each frame having suitable flanges 23 and 24 clamped to the marginal or border portions of the front 1 about the aperture 20 by suitable 70 securing means, such as bolts 25 or the like. The outer frame has an aperture 26 which is closed a transparency 27 of any suitable material, such as glass, mica, transparent compositions, and the like, held in place by suitable springs 28. 75 The inner window frame 22 has a corresponding-

ly registering aperture 29 opposite which is the light-filter lens device.

The latter device comprises a pair of telescopically engaged frame components 30 and 31 provided with apertures 32 and 33 to register with the apertures 29, 20 and 26 referred to above, the telescopical engagement being by way of slideable and overlapping resilient flanges 34 and 35 (see Fig. 2) having any suitable means, such as registering projections and depressions (not shown) for holding the components together. The component 32 is secured to the frame 22 in any suitable manner, as by brazing, welding, or the like.

At the rear of the frame part 31 is located another transparency 36 in a frame 37 having an aperture 38 in registry with the apertures 33, 32, 29, 20 and 26 referred to above. The frame 37 has resilient flanges 39 at its sides to telescopically slide over the sides of the lens frame, and to be releasably held therewith by suitable means, such as registering projections and depressions (not shown).

In the lens frame 30-31 vertically slides the light-filter lens 40 which is carried in a holder or carrier frame having a lower cross bar 41, vertical side bars 42 and 43, and upper stubs 44 and 45 overhanging the upper corners of the lens 40. The frame parts 30 and 31 are elongated downwardly (see Fig. 1) to provide an extension below the window structure in general so as to provide space for the downward movement of the lens 40 and its carrier. From the mid portion of the cross bar 41 depends a stem 46 which slides through a suitable opening 47 in the lower end of the lens frame 30-31 (see Figs. 1 and 5).

The vertical carrier parts 42 and 43 and the narrow portions only of the lateral margins of the lens 40 slide between guide shoulders 48 and 49, whereby the main surface area on both sides of the lens 40 will be spaced from the frame components 30 and 31 so that it will be impossible to mar, as by scratching or otherwise injuring, such surfaces of the lens.

The distance between the guide shoulders 48 and 49 is preferably greater than the thickness of the lens carrier (see Fig. 1), so that lenses of various thicknesses may be used, even though being in some cases thicker than the carrier itself. In all cases only the narrow edge portions of the lens will rub against the guide shoulders 48 and 49.

The device is designed so that when the operator is in normal position looking horizontally through the window and lens the lines of vision will be through the upper portion thereof, that is, where the lens first opens so that the operator may see through upon the first opening of the lens even though such opening be but slight.

Therefore, so that the window may be at the proper vertical height relative to the particular position of the operator's eyes, the vertical slots 12 provided in the side walls 2 and 3 of the shield afford a means for vertical adjustment of the shield to bring the upper edges of the openings in the window and of the lens assembly about in line with the eyes, preferably slightly above the lines of collimation of the eyes. Such adjustment is made (see Fig. 3) by loosening the nuts 17 (at both sides of the head) and raising or lowering the shield within the limits of the length of the slots 12 to the desired position, and then tightening the nuts.

In manufacture, the shield may not be uniform or symmetrical, as for example the head harness might be sitting correctly on the operator's head

but the shield may not be vertical and hence the two eyes of the operator may not look along a plane parallel to the upper edge of the apertures of the window device. Hence, the adjustment of the shield may need to be made only in respect to the slot 12 at one side of the operator's head to bring the lines of collimation of the eyes into the plane parallel to the upper edges of the apertures, particularly the lens aperture, of the device.

Extending about the front and sides of the lower portion of the operator's head, as the lower jaw, is located a bow-shaped lever 50 pivoted at its ends by way of pivot means 51 secured to the side walls 2 and 3 of the shield and extending through slots 52 provided in the bow lever. At the forward and mid portion of the bow lever 50 is provided an aperture through which extends a rod 53 having a head 54 engaged with the rear side of the lever and a threaded shank 55 carrying a thumb nut 56 for clamping the rod to the lever. The forward end portion of the rod 53 is smooth and extends through an aperture 57 of a link 58 pendulously connected to a screw 59 secured to the lower end portion of the stem 46 of the lens carrier. The aperture 57 is of amply greater diameter than that of the portion of the rod 53 extending through such aperture.

Hence, it is apparent that the downward and upward movements of the rod 53 with the lever 50 will cause a similar downward and upward movement of the lens and its carrier. If the axis of the lever 50 be in a plane not perpendicular to the line of movement of the lens there will be a slight component side movement of the rod 53. Hence, by having the rod 53 extend through the link 58 pivoted to the lens carrier, such component side movement does not cause a similar side or lateral movement of the lens carrier, and, hence, there is no possibility of the lens carrier becoming jammed or wedged in its race. Any component lateral movement that might be present will be compensated for by a corresponding swing of the link 58.

When assembling the device the rod 53 may not be centrally below the center of the lens and its carrier, but may be laterally to one side or the other. That may be due to manufacturing variances, or to the guard becoming deformed, as by warping, etc. To shift the rod 53 to central position the pivot means 51 at the ends of the bow lever 50 are loosened so that either or both slotted ends of the lever may be moved rearwardly or forwardly depending upon in which lateral direction the rod 53 is to be shifted, and then the pivot means are tightened.

Springs 60 (see Fig. 1) are connected to the lever 50 and to the side walls 2 and 3, as by screws 61 or the like, to raise the lever 50 after it has been moved down and released.

To the forward and mid portion of the bow lever 50 is secured an angle shaped bracket having a vertical leg 62 provided with a slot 63 through which the rod 53 extends. This leg part 62 is clamped between the mid portion of the lever 50 and the thumb nut 56. It may be vertically adjusted within the limits of the slot 63. From the lower end of the leg 62 extends rearwardly and downwardly the other leg 64 of the bracket, which leg 64 also has a slot 65 for an adjustment later described.

On the bracket leg 64 is adjustably secured a chin part comprising an upwardly extending lobe 66 having an inclined face 67 which abuts the forward portion of the operator's chin when the

guard is in upright position as shown in Fig. 1, and a lower rearwardly extending and inclined lobe 68 normally slightly spaced below the chin of the operator, and depressible by the chin when lowered, by opening of the mouth, for that purpose.

The chin part just described is connected to the bracket leg 64 by a suitable bolt and thumb nut means extending through the slot 65. The adjustment is made so that when the lobe wall 67 contacts or abuts against the operator's chin the shield wall 1 is in such position relative to the operator's face that the lines of collimation of the operator's eyes will be through the upper part of the lens 40 and the lens aperture as above described. In other words, the chin part lobe 66-67 acts as an abutment or limit stop, when the shield is swung downwardly from the dotted line to the full line positions shown in Fig. 1, whereby such lobe contacts the chin.

The space between the chin and the lobe 68 beneath it provides for a certain amount of clearance for the natural movements of the chin, as when swallowing, or chewing gum or tobacco, etc., wherein there is very little perceptible movement of the chin. But when the mouth is opened further although but for a slight way the chin will then engage the lobe 68 and depress it and accordingly cause a downward swing of the lever 50 with the rod 53, and a similar downward movement of the lens 40. The opening thus produced above the upper edge of the lens 40 will be as wide or deep as the operator desires, depending upon the degree of chin movement he makes. In other words, it is not usually necessary to effect wide openings of the lens aperture but only small openings for the purpose of affording the particular clear and unfiltered view that might be necessary between welding steps of the process of welding.

It will be noted that the width and height of the lens 40 are greater than the width and height of the apertures 32 and 33 so that when the lens 40 is in closed position its margins overlap the frame borders of the apertures referred to and there is no leakage of light past the edge or edges of the lens 40.

The upper bar of the lens carrier is cut away so that the line of vision can be had directly over and past the upper edge of the lens 40 when opened, even slightly. That avoids confusion that would occur with an opaque bar at the upper edge of the lens 40. Also, it reduces the amount of chin movement that would be necessary to move the lens open to the extent to clear the bar at the upper edge of the lens.

In some cases it might be desirable to have the lens open for longer periods of time than when merely opening and closing the lens for short instants of time by small chin movements as described above, and for preventing jaw muscle fatigue. In such case the operator may open his mouth wide bringing the chin low so as to swing the lever 50 and the rod 53 to the dotted line position shown in Fig. 1 whereby the end 69 of the rod 53 will enter an aperture 70 of a spring 71, the spring being first deflected by the end 69 of the rod 53 pressing against the spring above the aperture 70 and then springing back to lock the rod end 69 in the aperture 70. The lens will then be fully open and the operator may perform the work he needs to do then with a clear view and without tiring his jaw muscles. When ready to return to welding the operator need only insert a finger in the lower part of the guard to press forward the spring 71 and release the rod 53

which will return to upper position by the force of the springs 60.

It will be noted that the lever 50 is normally a few degrees above the horizontal plane, when the guard is in vertical position, and is swung first to such horizontal plane and then past it for a few degrees, for the ordinary or usual manipulation by the chin to open the lens at the upper portion of the aperture for the small openings described above. To illustrate the extent of such opening the end portion 69 of the actuating rod 53 is shown in dot and dash lines below the full line position thereof in Fig. 1.

The point of application of the chin with the chin actuated lobe 68 is about half way between the axis of the lever 50 and the point of application of the rod 53 with the link 58, so that for a given movement of the chin the lens movement is twice as much,

20 While having herein described and upon the drawings shown an illustrative embodiment of the invention it is to be understood that the invention is not limited thereto but comprehends other constructions, details, arrangements of parts, features, or the like, without departing from the spirit of invention.

Having thus disclosed the invention, I claim:

1. In a welder's helmet which comprises a head harness, a shield carrying a window with a lens means in the front wall thereof and having side walls pivotally connected to the sides of the harness; the combination of a chin operated means for opening and closing the lens means, comprising a bow shaped lever having its ends pivotally connected to the side walls of the shield and its mid-section located forwardly of the chin of the operator, a lens actuating element secured to said mid-section and extending forwardly thereof, a spring connected to a side wall and to said bow shaped lever for normally holding the lever in upper position, pivotal means connected to the lens means and to said lens actuating element, and a chin engaging member connected to said lever for operating the lens upon the lowering of the chin against said chin operated means, said pivotal connecting means between said lens means and said lens actuating element comprising a pendulous link pivotally connected to the lens means and provided with an end portion of said lens actuating element for the pendulous link to have a component lateral swing when the lens actuating element is moved with said lever.

55 2. In a welder's helmet which comprises a head harness, a shield carrying a window with a lens means in the front wall thereof and having side walls pivotally connected to the sides of the harness; the combination of a chin operated means for opening and closing the lens means, comprising a bow shaped lever having its ends pivotally connected to the side walls of the shield and its mid-section located forwardly of the chin of the operator, a lens actuating element secured to said mid-section and extending forwardly thereof, a spring connected to a side wall and to said bow shaped lever for normally holding the lever in upper position, pivotal means connected to the lens means and to said lens actuating element, and a chin engaging member connected to said lever for operating the lens upon the lowering of the chin against said chin operated means, said pivotal connecting means between said lens means and said lens actuating element comprising a pendulous link

pivotedly connected to the lens means and provided with an aperture through which extends an end portion of said lens actuating element for the pendulous link to have a component lateral swing when the lens actuating element is moved with said lever, and means for centering said lens actuating element below the center of the lens means, comprising means associated with said pivotal connection between said side walls and said bow lever, which means includes the provision of slots in the end portions of said bow lever and through which extend the said latter pivotal connections, and clamping means connected to said pivotal connections for adjustably clamping the slotted end portions of the bow lever.

3. In a welder's helmet which comprises a head harness, a shield carrying a window with a lens means in the front wall thereof and having side walls pivotally connected to the sides of the harness, the combination of a chin operated means for opening and closing the lens means, comprising a bow shaped lever having its ends pivotally connected to the side walls of the shield and its mid-section located forwardly of the chin of the operator, lens actuating element secured to said mid-section and extending forwardly thereof, a spring connected to a side wall and to said bow shaped lever for normally holding the lever in upper position, pivotal means connected to the lens means and to said lens actuating element, an angular bracket having an upright leg with means for adjustably connecting said upright leg to said mid-section of the lever, and a rearwardly inclined leg extending below the chin of the operator, and a chin engaging member carried by said inclined leg and having means for adjustably connecting said chin engaging member to said inclined leg.

4. In a welder's helmet which comprises a head harness, a shield carrying a window with a lens means in the front wall thereof and having side walls pivotally connected to the sides of the harness, the combination of a chin operated means for opening and closing the lens means, comprising a bow shaped lever having its ends pivotally connected to the side walls of the shield and its mid-section located forwardly of the chin of the operator, lens actuating element secured to said mid-section and extending forwardly thereof, a spring connected to a side wall and to said bow shaped lever for normally holding the lever in upper position, pivotal means connected to the lens means and to said lens actuating element, an angular bracket having an upright leg with means for adjustably connecting said upright leg to said mid-section of the lever, and a rearwardly inclined leg extending below the chin of the operator, and a chin engaging member carried by said inclined leg and having means for adjustably connecting said chin engaging member to said inclined leg, said chin engaging member comprising an upright portion for contacting the front portion of the chin, and a rearwardly inclined portion normally slightly spaced below the chin of the operator but engageable by the lower part of the chin.

5. In a welders' helmet which comprises a head harness, a shield carrying a window with a lens means in the front wall thereof and having side walls pivotally connected to the sides of the harness, said lens means comprising a frame provided with upper and side channels and a lower opening, a lens carrier having a lower bar adapted to pass through said lower opening, upright side bars, and stubs at the upper ends of the side bars, and a light filtering lens piece located between said side bars, above said lower bar, and with its upper corners below said stubs for leaving the upper edge of the lens piece free between said stubs.
6. In a welder's helmet which comprises a head harness, a shield carrying a window with a lens means in the front wall thereof and having side walls pivotally connected to the sides of the harness, said lens means comprising a frame provided with upper and side channels and a lower opening, a lens carrier having a lower bar adapted to pass through said lower opening, upright side bars, and stubs at the upper ends of the side bars, and a light filtering lens piece located between said side bars, above said lower bar, and with its upper corners below said stubs for leaving the upper edge of the lens piece free between said stubs, said channels being wider than said bars and stubs to afford locating of lens pieces in the frame of different thickness.
7. In a welder's helmet which comprises a head harness, a shield carrying a window with a lens means in the front wall thereof and having side walls pivotally connected to the sides of the harness, said lens means comprising a frame provided with upper and side channels and a lower opening, a lens carrier having a lower bar adapted to pass through said lower opening, upright side bars, and stubs at the upper ends of the side bars, and a light filtering lens piece located between said side bars, above said lower bar, and with its upper corners below said stubs for leaving the upper edge of the lens piece free between said stubs, said lens piece having its edge portions overlapping the walls of said channels and the sides of said lower opening to exclude the passage of light between said walls and sides.
8. In a welder's helmet which comprises a head harness, a shield carrying a window with a lens means in the front wall thereof and having side walls pivotally connected to the sides of the harness; the combination of a chin operated means for opening and closing the lens means, comprising a bow shaped lever having its ends pivotally connected to the side walls of the shield and its mid-section located forwardly of the chin of the operator, a lens actuating element secured to said mid-section and extending forwardly thereof, a spring connected to a side wall and to said bow shaped lever for normally holding the lever in upper position, a chin engaging member connected to said lever for operating the lens upon the lowering of the chin against said chin operated means, and a latching means comprising a spring connected to a lower portion of the shield and in the path of movement of the lens actuating element, and provided with a catch element for locking with said lens actuating element.
